UNITED STATES PATENT OFFICE.

GEORGE A. SAGER, OF ALBANY, NEW YORK.

SEAT-CUTTING TOOL.

Application filed August 19, 1920. Serial No. 404,660.

To all whom it may concern:

Be it known that I, GEORGE A. SAGER, a citizen of the United States, residing at Albany, in the county of Albany and State of New York, have invented certain new and useful Improvements in Seat-Cutting Tools, of which the following is a specification.

This invention relates to an improved tool for cutting a seat at the inner end of a plug opening through a boiler back head whereby a boiler plug of the type shown in my co-pending application filed Aug. 19, 1920, Serial No. 404,659, may be employed upon the boiler.

The invention has as one of its principal objects to provide a tool which may be successfully operated at the outer side of the back head.

A further object of the invention is to provide a tool having a cutter of such construction that the cutter may be readily inserted or removed through the plug opening in the back head.

And the invention has as a still further object to provide a tool which will, without chattering, form a smooth annular beveled seat at the inner end of the plug opening.

Other and incidental objects will appear hereinafter.

In the drawings:

Figure 1 is a side elevation of my improved tool, the tool being arranged in position upon a boiler back head,

Figure 2 is a longitudinal sectional view taken medially through the tool,

Figure 3 is an end elevation showing the cutter in detail,

Figure 4 is a face view of one of the cutter sections,

Figure 5 is a fragmentary section showing the manner in which the cutter sections are inserted through the plug opening in the boiler back head, and

Figure 6 is a detail perspective showing the wrench employed in separating the cutter sections.

As previously intimated, the tool of the present invention is particularly designed for use in cutting a beveled seat at the inner end of a plug opening through the back head of a locomotive boiler so that a plug of the type shown in my co-pending application previously identified, may be employed upon the boiler. Since it is impossible to work upon the boiler back head from the inner side thereof, it accordingly becomes neces-

sary to provide a tool the cutter of which may be readily inserted through the plug opening in the back head and then brought into position for cutting the seat at the inner end of said opening. Further, as will be seen, it is also necessary that the cutter may be readily removed through the plug opening after the operation of cutting the seat has been completed.

In carrying the invention into effect, I employ a shell or body 10 radially enlarged at its lower end and provided with spaced depending foot lugs 11. Freely journaled through the shell is a feed screw or bar 12 provided at its inner end with a reduced extension 13 defining an annular shoulder 14 at the junction of said extension with the body of the screw. Mounted upon said extension is the cutter employed. This cutter is formed of mating oblong sections which, for convenience, have been indicated at 15 and 16 respectively, the section 16 being provided with a flat upper face to seat against the shoulder 14 of the feed screw while the section 15 is thickened at its lower side and is thus reinforced and provided with a convex lower face. Through the outer end of the extension 13 is engaged a pin 17 removably securing the cutter sections upon the extension. Formed on the upper sides of the sections at their ends are arcuate beveled cutting faces 18 and formed in the confronting sides of the sections are medial transverse channels 19, the channel of each section being adapted to receive the intermediate portion of the other section. Consequently, as best shown in Figure 3, the sections may be brought together and interlocked in assembled relation extending at substantially right angles to each other when the cutting faces 18 of the sections will, in effect, provide an annular cutting surface. It is now to be observed that the extension 13 is provided with a right hand thread and the cutter section 15 is threaded to engage the thread of the extension while the cutter section 16 is loosely fitted upon the extension.

Loosely surrounding the outer end portion of the feed screw is a thrust washer 20 seating against the outer end of the shell 10 and resting against said washer is a collar 21 splined upon the feed screw, the feed screw being, as shown in dotted lines in Figure 2, provided with a longitudinal channel in which engages a feather 22 coupling the collar with said

screw to turn therewith while at the same time permitting the collar to slide longitudinally of the screw. Resting against the collar is a thrust washer 23 and coaxing with this washer is a feed nut 24. At its outer end portion, the feed screw is provided with a left hand thread engaged by the feed nut and, as will be observed, the nut is provided with an annular series of spaced openings 25 in which a suitable tool may be selectively engaged for rotating the nut. Formed on the feed screw at its outer end is a squared terminal 26 with which a wrench or ratchet may be engaged for rotating said screw.

In order that the operation of my improved tool may be accurately understood I have, in the drawings, shown the device in connection with the back head 27 of a locomotive boiler. To accommodate my improved plug, as shown in my co-pending application, the back head is first formed with a circular plug opening 28 therethrough. The tool of the present invention is then employed to form a beveled seat at the inner end of this opening. To accomplish this operation, the cutter section 15 is, as shown in Figure 5, first threaded to the outer end of the extension 13 of the feed screw when the cutter section 16 is then moved away from the section 15 so that the section 15 may, as also suggested in this figure, be inserted through the opening 28 in the back head. This done, the feed screw is rocked to insert the section 16 of the cutter through said opening in a similar manner. By manually pulling outwardly upon the feed screw until the section 16 contacts the inner side of the back head at the opening 28, interlocking with the section 15 of the cutter, the feed screw may then be rotated clockwise for threading the cutter section 15 inwardly upon the extension 13 of the feed screw until, as shown in Figures 1 and 2, the section 16 of the cutter is jammed against the shoulder 14. The shell 10 is then positioned over the opening 28 at the outer side of the back head for centering the cutter with respect to said opening and the feed nut adjusted for binding the cutter against the rim of the opening at its inner end. Consequently, as will be seen, a wrench or ratchet may then be applied to the terminal 26 of the feed screw for rotating this screw and revolving the cutter to form a beveled seat at the inner end of the opening, the nut 24 being, of course, adjusted as desired to feed the cutter to the work. Since, as previously noted, the beveled cutting faces of the cutter sections will, when the cutter sections are assembled, form practically a continuous annular cutting surface, chattering of the cutter will be eliminated while the cutter will operate to form a smooth beveled seat at the inner end of the opening through the back head. As

the cutting operation progresses, oil may be applied to the cutting faces of the cutter through the openings between the foot lugs 11 of the shell 10 and, of course, the progress of the work may also be observed through these openings. To remove the tool, the feed nut 24 is first loosened and in order to facilitate separation of the sections of the cutter I provide, as shown in Figure 6, a wrench 29. The shank of this wrench is curved laterally at its inner end portion and is provided with a depending head 30. After loosening the feed nut 24, the shank of the wrench 29 is inserted through one of the openings between the foot lugs 11 of the shell and the head 30 of the wrench engaged in one of the angles between the projecting end portions of the cutter sections. Consequently, the cutter section 15 may then be readily held stationary so that the feed screw 12 may be rotated counter-clockwise for threading said section to the outer end of the extension 13. Then, by moving the cutter section 16 inwardly away from the cutter section 15 the feed screw may be rocked for withdrawing first the section 16 and then the section 15 through the opening in the back head and releasing the tool.

Having thus described the invention, what is claimed as new is:

1. A tool for forming a plug seat at the inner end of a boiler sheet opening including a feed screw, means engageable with the outer side of the sheet for supporting the screw, and a cutter carried by the screw and engageable with the periphery of the opening at the inner side of the sheet, the cutter being formed of interlocking sections. 95

2. A tool for forming a plug seat at the inner end of a boiler sheet opening including a feed screw, means engageable with the outer side of the sheet for supporting the screw, and a cutter carried by the screw and engageable with the periphery of the opening at the inner side of the sheet, the cutter being formed of interlocking separable sections individually removable through said opening. 105

3. A tool for forming a plug seat at the inner end of a boiler sheet opening including a feed screw, means engageable with the outer side of the sheet for supporting the screw, and a cutter mounted upon the screw and engageable with the periphery of said opening at the inner side of the sheet, the cutter being formed of interlocking sections 110 one loose upon the screw and another threaded thereon. 120

4. A tool for forming a plug seat at the inner end of a boiler sheet opening including a feed screw, means engageable with the outer side of the sheet for supporting the screw, the screw being formed with a reduced extension, and a cutter carried by said extension and engageable with the periphery 125 130

of said opening at the inner side of the sheet, the cutter being formed of interlocking sections one loose upon the extension and the other threaded thereon.

5. A seat cutting tool including a bar, means for operatively supporting the bar, and a cutter carried by the bar and formed of separable sections, one of the sections being loose on the bar and another of said sections being engaged directly with the bar

and rotatably adjustable thereon to abut the first section interlocking therewith.

6. A seat cutting tool including a bar, means for operatively supporting the bar, and a cutter carried by the bar and formed of crossed oblong interlocking separable sections provided at their ends with working faces.

In testimony whereof I affix my signature.
GEORGE A. SAGER. [L. s.]
